UNITED STATES PATENT OFFICE

FRANK MARTINDELL, OF WESTERN SPRINGS, ILLINOIS

DESIGN FOR A TOY MACHINE GUN

Application filed February 12, 1932. Serial No. 42,820. Term of patent 7 years.

To all whom it may concern:

Be it known that I, FRANK MARTINDELL, a citizen of the United States, residing at Western Springs, in the county of Cook and State of Illinois, have invented a new, original, and ornamental Design for Toy Machine Guns, of which the following is a specification, reference being had to the accompanying drawings, forming part thereof.

Fig. 1 is a top plan view of a toy machine gun embodying my new design.

Fig. 2 is a side elevation of the same.

I claim:

The ornamental design for a toy machine gun as shown.

FRANK MARTINDELL.
